UNITED STATES PATENT OFFICE.

SAMUEL B. GOFF, OF CAMDEN, NEW JERSEY.

DEVICE FOR APPLYING ADHESIVE MATERIAL TO BOTTLES, &c.

950,207.

Specification of Letters Patent. Patented Feb. 22, 1910.

Application filed September 1, 1909. Serial No. 515,582.

To all whom it may concern:

Be it known that I, SAMUEL B. GOFF, a citizen of the United States, residing in the city and county of Camden, State of New Jersey, have invented a new and useful Device for Applying Adhesive Material to Bottles, &c., of which the following is a specification.

My invention consists of a device embodying means for presenting adhesive material so as to be applied to a bottle, etc., by bringing the latter in contact therewith, furthermore of means for returning the surplus material to the supplying vessel, and next of means for replenishing said vessel with fresh material, as will be hereinafter described, the novel features being pointed out in the claims.

For the purpose of explaining the invention, the accompanying drawings illustrate a satisfactory reduction of the same to practice, but the important instrumentalities thereof may be varied, and so it is to be understood that the invention is not limited to the specific arrangement and organization shown and described.

Figure 1 represents a perspective view of an adhesive-material applying device embodying my invention. Fig. 2 represents a longitudinal section thereof. Fig. 3 represents a transverse section thereof. Fig. 4 represents a partial end view and partial vertical section of a part of the device.

Similar letters of reference indicate corresponding parts in the figures.

Referring to the drawings:—A designates a casing or vessel within which are the vertical partitions forming the well B, in which is located the plunger C, which is tubular or of the form of a sleeve, the same depending from the follower D, a portion of the floor of which at the top of said sleeve being perforated forming the diaphragm E on which is supported the pad F of absorbent material, the same being adapted to have a bottle placed thereon and have a side thereof in contact with the pad. The follower has a depending rim G, which enters the casing A and provides a guide for the former in the descending and ascending motions thereof.

On the bed or cross piece J at an end of the follower is a pad or cushion H of pliable material, which in the present case is retained in position by the lips J' which rise from said piece and embrace said pad as

most plainly shown in Fig. 4. Connected with the adjacent end of the casing A is the funnel or supply receptacle K, the same having a bottom T, in which is a port M, the same being over the pad H, so that in the normal position of parts, said pad is in contact with said bottom, whereby the port in the latter is closed, said port and pad acting after the manner of a valve and valve seat.

In the well C is the block N, on the top of which is sustained the springs P, which are adapted to have the follower D rested thereon, so that when the latter is depressed, said springs are contracted and the sleeve C is caused to descend and dip into said well, around said block. In the sides of said sleeve are ports Q for overflow purposes, as will be hereinafter more particularly referred to. Surrounding the pad F and adjacent portions of the floor of the follower is a wall R, which serves to inclose a bottle and retain it true when on said pad F. The casing A is seated in a pan or tray S, which is adapted to receive the drip of the adhesive material from said casing.

The operation is as follows:—Suitable adhesive material is poured into the vessel A and so fills the well B to the proper height, said well constituting the font of the device, the funnel K being also supplied with adhesive material. An article, say a bottle, is placed on the pad F and pressed downwardly, whereby the follower D descends and owing to the sleeve C, the material in the well is forced against and through the diaphragm E and injected against said pad, thus saturating the same and thereby applying the material to the bottle, the latter then being removed and found ready for a labeling operation, the movable parts then returning to normal position. As the follower and consequently the sleeve descends and the material in the well is subjected to pressure by the diaphragm E, some of the material overflows through the ports Q into the casing A and so returns to the well, as indicated by the arrows 1, thus relieving the pressure on the material in the sleeve. As the cross piece or bed J descends with the follower, the cushion N lowers from the base of the funnel K, thus uncovering the port M, when a quantity of material flows through the cushion H and enters the casing A and so supplies the latter with fresh material, replenishing the casing or well therein. When the follower returns to its normal position,

the cushion H closes against the port M, and so prevents the further flow of material from the funnel.

Having thus described my invention, what I claim as new and desire to secure by Letters Patent, is:—

1. In an adhesive - material applying - device, a font, a follower thereover, means for movably supporting said follower, an absorbent pad on said follower, a supplying receptacle, and a valve intermediate of said receptacle and font, said valve being adapted to be controlled by the motions of said follower.
2. In an adhesive - material - applying device, a vessel, a supplying receptacle on said vessel, the same having an outlet port, a follower, and means on said follower adapted to be moved against and from said port to close and uncover the same respectively.
3. In an adhesive - material - applying device, a vessel, a plunger adapted to enter the same, a resilient support for said plunger, whereby the latter may be returned to and held in normal position, a foraminous diaphragm connected with said plunger, an absorbent piece on said diaphragm, a material-supplying receptacle for said vessel, the same having an outlet valve, and a seat connected with said plunger adapted to open and close said valve by the motions of said plunger.
4. In an adhesive - material - applying device, a vessel, a plunger therein, a foraminous diaphragm carried by said plunger, and an absorbent on said diaphragm, said plunger being provided with a port for the overflow material therein on the descent of the same.
5. In an adhesive - material - applying de-

vice, a vessel, a movable member in said vessel and an absorbent carried by the same, said absorbent being adapted to be supplied with adhesive material from said vessel, a supplying receptacle adapted to communicate with said vessel, and a valve and valve seat respectively on said receptacle and member, said valve being adapted to be opened and closed by said seat by said movable member.

6. In an adhesive - material applying device, a font, a plunger adapted to dip into the latter, a slideable follower carrying said plunger, a piece of absorbent material on the open bottom of said follower, a stationary supply-receptacle for adhesive material, the same being in communication with said font, and a valve and valve seat respectively on said slideable follower and stationary supply-receptacle.

7. In an adhesive - material applying device, a font, a block partly occupying the same, a follower above said block, a plunger depending from said follower and adapted to dip into said font around said block, and a resilient support for said follower adapted to be seated on said block.

8. In an adhesive - material applying device, a font, a material-applying follower supported thereover, a supplying receptacle in communication with said font, and an automatically-acting valve intermediate of said receptacle and font, the same being adapted to be controlled by the motions of said follower.

SAMUEL B. GOFF.
